UNITED STATES PATENT OFFICE.

WILLIAM R. HILL, OF SYRACUSE, NEW YORK, ASSIGNOR TO THE PREMIER EGG CUP COMPANY, OF SAME PLACE.

DESIGN FOR AN EGG-CUP.

SPECIFICATION forming part of Design No. 23,898, dated December 25, 1894.

Application filed October 30, 1894. Serial No. 527,494. Term of patent 14 years.

To all whom it may concern:

Be it known that I, WILLIAM R. HILL, of Syracuse, in the county of Onondaga, in the State of New York, have invented and produced a new and original Design for Egg-Cups, of which the following, taken in connection with the accompanying drawings, is a specification.

Figure 1 is an elevation of an egg cup embodying my design; and Fig. 2 a vertical sectional view, taken on line 2-2, Fig. 1, these views being deemed necessary to fully illustrate the design.

The leading feature of my design consists in a substantially circular body having a contracted upper portion formed with a convex top face and having the outer faces of diametrically opposite parts formed substantially parallel; a central portion formed with an annular shoulder at the base of said upper portion and with a contracted lower end and having the upper extremities of the outer faces of diametrically opposite parts formed substantially parallel, and the lower extremities of said faces disposed in planes forming, essentially, corresponding sections of substantially elliptical planes; and a downwardly flaring base portion having the outer faces of diametrically opposite parts disposed in substantially ogee planes.

A is the substantially circular body of my design, and a a', and a³ are, respectively, upper, central, and base portions. The upper portion a is of less diameter than the central portion a', and its upper part is formed with a convex top face a³ and spiral ribs and grooves a⁴ a⁵, and its lower part a⁶ is substantially plain. The outer faces a⁷ a⁸ of diametrically opposite parts of the upper portion a are substantially parallel, and the cen-

tral part of said portion is formed with an annular shoulder a⁹. The central portion a' is formed with an annular top shoulder a⁹ projecting from the plain lower part a⁶ of the upper portion a, and with a gradually contracted lower end a¹⁰ having its lower extremity formed of less diameter than the upper part a. The upper extremities a¹¹ of the outer faces of diametrically opposite parts of the central portion a' are formed substantially parallel, and the lower extremities a¹² of said faces are disposed in planes forming, essentially, corresponding sections of substantially elliptical planes. The outer face of the central portion a' is provided with ornamentation a¹³ representing flowers, leaves, &c., or other objects or designs. The base portion a² flares downwardly from the contracted lower end of the central portion a', and is formed of less diameter than the upper portion a. The outer faces a¹⁴ of diametrically opposite parts of the base portion a² are disposed in substantially ogee planes, and the lower face of said portion a² is formed with a raised central part a¹⁵.

My design is very pleasing in appearance, and adds greatly to the salability of the egg cup.

What I claim is—

The design for an egg cup, substantially as herein shown and described.

In testimony whereof I have hereunto signed my name, in the presence of two attesting witnesses, at Syracuse, in the county of Onondaga, in the State of New York, this 23d day of October, 1894.

WILLIAM R. HILL.
